Filed Feb. 3, 1970, Ser. No. 21,227

Term of patent 14 years

Int. Cl. D21—02

U.S. Cl. D34—5

FIG. 1 is a front elevational view of a golf putter head showing my new design.

FIG. 2 is an end view of FIG. 1.

FIG. 3 is a top plan view of FIG. 1.

FIG. 4 is a bottom plan view of FIG. 1.

FIG. 5 is a rear elevational view of FIG. 1.

The characteristic feature of my design resides in the combination of the particular club head with a vertical slot across the central face that intersects a horizontal slot which is parallel to the face of the head and surfaces at the top and bottom of the head as shown.

I claim:

The ornamental design for a golf putter head, substantially as shown and described.
